To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of vertical stripes filled with flowers and leaves with light vertical lines on each side of said vertical stripes and light interlacing vines of leaves and flowers arranged in the form of wreaths interlacing each other and said vertical stripes, as represented in the accompanying drawing.

The border for the said design is formed of vase-like ornaments arranged above said vertical stripes with a large group of roses and leaves in said vase-like ornaments and palm-like ornaments on each side of said vase-like ornaments and connected with said light vertical lines, as shown in the drawing.

What I claim is—

The design for wall-paper herein shown and described.
